EGIDIO TORRE, OF GENOA, ITALY

PILOT-VALVE-STEERED SLIDE VALVE

Application filed March 20, 1930, Serial No. 437,507, and in Italy January 11, 1930.

This invention relates to pilot-valve steered slide valves, which provides an arrangement adapted for use on any slide valve device, in which the main valve displacements are in

5 relation with the displacements of a pilot valve controlled by a float or other control.

The main object of the invention is to provide a device of the kind referred to, which is of reduced volume and weight and in which

10 the maximum angular displacement of the pilot-steering lever is maintained within a small angle, while permitting a suitably long stroke of the slide valve by maintaining at the same time the control lever very short,

15 these results being attained by mounting the said lever on a pair of slidable stems permitting this lever to rest substantially horizontal at different heights, by way of its ability to exchange alternatively with one another the

20 fulcrum and the resistance points from one end to the opposite one.

Another object of the invention is to provide a device of the above character in which the control lever is a float lever, the whole device being of low cost and of simple and rugged construction, ensuring a reliable service under rough working conditions while avoiding the costly precision finishings of the slidable parts.

25 An embodiment of the invention fitted to a closed-cycle water feed for steam boilers is illustrated in the annexed drawing, in which:

Figure 1 shows a pilot-steered float-controlled feed distributing valve embodying the 30 invention, and

Figures 2, 3 and 4 show details of construction and fitting of the control-lever (float-lever) to the stems connected to the main and to the pilot valve, respectively.

35 The feed control comprises the usual slide valve body A fitted with three flanged nozzles E, S and C to which the pipes are connected leading to the delivery side of the suction pump from the condenser, to the hot water well and to the condenser respectively.

Within this valve body A the distributing slide valve (or, in the present instance, a piston valve) V is mounted, which in its middle position, as shown, closes the communication 40 between any two of the three nozzles E, S,

C, while when it is in its upper position puts into communication S with E, and in its lower position establishes the communication between S and C.

45 A small amount of water under pressure is constantly fed through E, adjacent chamber J and pipe O to a hand-operated bypass valve K through which it is fed to pipes M and N leading to narrow calibrated passages F and F' opening respectively into the upper 50 and lower ends of said valve body A.

55 Within valve V the pilot valve housing B is fitted having three sets of openings 1, 2 and 3, bored at different heights and of which the upper and lower ones, 2 and 3 respectively open into the upper and lower slide valve chamber, while the middle ones 1 open into a space U in communication with nozzle C and therefore with the condenser.

60 Within this valve body B the sliding pilot valve D is mounted, preferably formed as clearly shown and which in its middle position closes the communication of the condenser with the upper and lower chamber of main valve body A, while in its upper and 65 lower positions establishes the communication of the condenser with the upper and lower valve body A chambers respectively.

65 The float casing or chamber H is tightly 70 fitted to valve body A and is arranged in correspondence of the mean water level of the condenser, to the upper and lower part of which it is connected through Z and Z' respectively and thus the water within chamber H is at level with the condenser water.

75 Float G is integral of lever L, forked at its end opposite to the float, as shown Figure 4, for receiving the smoothed end portions of valve stems I and P.

80 Lever L is pivoted at X to stem I and it 85 terminates further with an horizontally slotted or double-forked head Y receiving the pivot member X' fastened to valve stem P. The particular construction of lever L and its connection with stems I and P are clearly 90 shown Figures 2, 3 and 4.

95 In the present instance or generally in the case of a piston valve, the upper portion of stem P terminates with an annularly grooved head W positively connected to valve V 100

through an annular rib formed within the lower part of said valve V. The upper end of stem I is somewhat loosely connected to pilot valve B.

The operation is as follows: Assuming the float G to be in its middle position and lever L to be substantially horizontal viz. in the position in which valves V and B are in their middle position, the device remains inoperative, but as soon as the water level in the condenser rises by way of a refuse of water by the boiler, the water within chamber H raises the float G and valve D is pushed upwardly uncovering ports 2 and thus establishing the communication between the port C (which, as said, is connected to the condenser) and the upper piston valve chamber, and thus valve V is sucked up by the vacuum in the condenser and in addition is pushed up by the pressure water forced through port F'. Valve V by sliding upwardly causes the pilot valve body B to slide upon valve D until complete closure of ports 2. In this moment lever L is again substantially horizontal but in a higher position than the former one.

As it is apparent, the fulcrum of lever L is at X' when the pivot valve is directly steered by the float, and is within the float when acted upon by main valve V.

It is further clear that the same operation is repeated all times the water level in the condenser rises, and when ports 2 are uncovered, the water from the delivery of the pump connected to E is discharged through S to the hot water well.

On the contrary when the level in the condenser sinks the operation of the device is reversed and valve V being sucked down establishes the communication between the condenser and the hot water well from which the water, having been previously deaerated, passes to the said condenser and thence to the boiler.

When the boiler should work in a open cycle, valve V is raised by hand by means of the screw stem R operated by hand wheel T.

From the foregoing it is also apparent that the maximum angle of oscillation of lever L is limited by an amount just sufficient to steer the pilot valve D to uncover either of the sets of ports 2 or 3, the height of the pivotal connections X and X' of said float lever varying by an amount Q corresponding to the total maximum stroke of the piston valve V, and within these limits the lever L can be always brought in horizontal position whenever the equilibrium between feed and consumption is established. In this manner it is possible to reduce the volume of the float chamber and the length of the float lever, while insuring a powerful and swift steering of the valves.

The particular connection of the valve stems P and I permits of a certain amount of lateral play at the points and further, in the case of a piston valve, permits a free revolution

of valve V under the tangential flow of water from E to S or from S to C.

It is to be understood that the embodiment as described and shown is only one of the many possible constructions within the limits of the invention or the scope of the appended claims, and that the valve-controlling lever might be operated also by other means, instead of a float.

Having thus described my invention, I claim:

1. In pilot-valve controlled slide valves, the arrangement within the slide valve of a pilot valve body, a pilot valve within this body, a slidable stem depending from the slide valve, a second slidable stem depending from the pilot valve and complementary to the first named stem and a control lever pivotally attached to both said slidable stems and having a projecting portion adapted to be acted upon by the control means.

2. A distributing slide valve comprising a valve body, pipe connections integral of the valve body, a float chamber fitted to said valve body, a slide distributing valve within said valve body, a pilot valve body integral of the slide valve having ports opening into the slide valve chambers, a pilot valve within this body adapted to establish communication between different pilot valve ports and a pair of slidable stems connected to the distributing valve and to the pilot valve, respectively, a float within the float chamber, a lever attached to this float and pivotally connected both to the stem of the distributing slide valve and to the stem of the pilot valve, so as to permit the fulcrum of the lever to pass alternatively from the end that is connected to the distributing valve stem, to the float end.

3. A distributing slide valve according to claim 1, in which the slide valve body is provided with three tubular pipe connections or ports situated at different heights, the slide valve in its middle position intercepting the communication between the middle port and either of the other ports, while in its upper and lower positions establishes the communication with the upper or the lower port respectively.

4. A distributing slide valve comprising a valve body, pipe connections at different heights of this valve body, a float chamber fitted to said valve body, a slide distributing valve within said valve body, adapted to intercept the communication of the middle pipe connection with the upper and the lower ones and to establish the communication in their upper and lower positions, a pressure water bypass pipe opening into upper and lower calibrated ports within the valve body, a hand operated valve controlling the passage of the said pressure fluid, a pilot valve body integral of said slide valve and having ports opening into the upper and lower slide

valve chambers and into the passage communicating with one of the ports in the slide valve body, a pilot valve within this body adapted to establish the communication between the middle port in the pilot valve body and either of the upper and lower ports therein and a pair of slidable stems connected to the distributing valve and to the pilot valve respectively, a float within the float chamber, a lever attached to this float and pivotally connected both to the stem of the distributing slide valve and to the stem of the pilot valve, so as to permit the fulcrum of the lever to pass alternatively from the 15 end connected to the distributing valve stem, to the float end.

5. A distributing slide valve according to claim 2, comprising means for manually operating said valve.

20 6. A distributing slide valve according to claim 2, in which the distributing and pilot valves are cylindrical or piston valves and are rotatably connected to depending slid- 25 able stems to which the float lever is pivotally attached so as to permit also a certain amount of lateral play of the parts, and a rotation of the piston valves within their bodies and about the slidable stems.

In testimony whereof I have affixed my
20 signature.
